OVEN RACK

Filed Sept. 16, 1924

Patented Mar. 17, 1925.

1,530,226

UNITED STATES PATENT OFFICE.

DEWEY H. BITNEY, OF ALBION, MICHIGAN, ASSIGNOR TO UNION STEEL PRODUCTS COMPANY, LTD., OF ALBION, MICHIGAN.

OVEN RACK.

Application filed September 16, 1924. Serial No. 738,023.

To all whom it may concern:

Be it known that I, DEWEY H. BITNEY, a citizen of the United States, residing at Albion, county of Calhoun, State of Michigan, have invented certain new and useful Improvements in Oven Racks, of which the following is a specification.

This invention relates to improvements in oven racks.

10 The main object of this invention is to provide an improved rotatable oven rack which may be readily adapted to ovens of different dimensions.

15 A further object is to provide an improved rotatable oven rack which is light in weight and at the same time strong and durable.

A still further object is to provide an oven rack having these advantages which is economical to produce.

20 Objects pertaining to details and economies of my invention will definitely appear from the detailed description to follow.

I accomplish the objects of my invention by the devices and means described in the 25 following specification. The invention is clearly defined and pointed out in the claims.

A structure embodying the feature of my invention is clearly illustrated in the accompanying drawings forming a part of this 30 application, in which:

Fig. I is a plan view of my improved oven rack.

Fig. II is a side view thereof.

Fig. III is an enlarged detail section on a 35 line corresponding to line 3—3 of Fig. I.

Fig. IV is a perspective view of one of the support members.

Fig. V is a perspective view of the cross 40 piece of the support.

In the drawing similar numerals of reference indicate similar parts in all of the views.

Referring to the drawing, I provide a pair of support members 1 adapted to rest 45 upon the shelf ledges of an oven, these support members being of general U-shape having inwardly projecting arms 2. The arms in the structure illustrated are inwardly offset at 3. These arms have longitudinal slots 50 4 therein in overlapping telescoping relation.

The arms are connected by bolts 5 arranged through the downturned ends 6 of the cross pieces 7, these cross pieces being 55 arranged in crossed relation as illustrated.

The bolts are arranged through the ears 6 so that the support members are adjustably connected and the cross pieces are effectively supported and provide reinforcing members for the support.

60 The cross pieces 7 have pivot holes 8 therein at their crossing point.

I provide a turntable consisting of the rim 9 and cross slats 10 of iron welded to the upper side thereof. A cross piece 11 is disposed below the slats 10 with its ends 12 resting upon and secured to the upper side 65 of the rim.

The pivot bolt 13 is arranged through this cross piece 11 of the turn table and through 70 the hole 8 of the cross pieces 7 so that the turn table is rotatably supported with its rim resting upon the arms of the support members. A washer 14 is arranged between 75 the cross piece 11 of the turn table and the upper cross pieces 7, see Fig. III.

With this arrangement of parts I provide 80 an oven rack that can be readily adjusted to ovens of different dimensions or sizes. The structure is very strong and rigid and at the same time may be formed of quite light material so that it is economical to produce and also easily handled.

Having thus described my invention what I claim as new and desire to secure by Letters Patent is:

1. An oven rack comprising a pair of support members having inwardly projecting parallel longitudinally slotted arms disposed in coacting telescoping relation, a pair 90 of cross pieces disposed in crossed relation between said arms and having downturned ends secured thereto by bolts disposed through said downturned ends and engaging said slots in said arms whereby the support members are adjustably connected, a turntable comprising a rim and slats secured to the upper side thereof, a cross piece disposed transversely below said slats and having its ends secured to the upper side of the rim, and a pivot disposed through said turn table cross piece and support cross pieces at their crossing point with the rim of said turntable rotatably supported by said support member arms.

100 105 110
2. An oven rack comprising a pair of support members having inwardly projecting parallel longitudinally slotted arms disposed in coacting telescoping relation, a pair of cross pieces disposed in crossed relation be-

tween said arms and having downturned ends secured thereto by bolts disposed through said downturned ends and engaging said slots in said arms whereby the support members are adjustably connected, a 5 turntable, and a pivot for said turntable disposed through said support cross pieces at their crossing point.

3. An oven rack comprising a pair of support members having inwardly projecting 10 parallel longitudinally slotted arms disposed

in coaxing telescoping relation, a pair of cross pieces disposed in crossed relation between said arms and secured thereto by bolts engaging said slots in said arms whereby 15 the support members are adjustably connected, a turntable, and a pivot for said turntable disposed through said support cross pieces at their crossing point.

In witness whereof I have hereunto set 20
my hand.

DEWEY H. BITNEY.
